UNITED STATES PATENT OFFICE.

EDWARD JURKOWSKI, OF BALTIMORE, MARYLAND.

IGNITING DEVICE.

1,397,637.

Specification of Letters Patent. Patented Nov. 22, 1921.

Application filed January 7, 1921. Serial No. 435,677.

To all whom it may concern:

Be it known that I, EDWARD JURKOWSKI, a citizen of Poland, residing at Baltimore, in the county of Baltimore City and State 5 of Maryland, have invented certain new and useful Improvements in Igniting Devices, of which the following is a specification.

This invention relates to certain new and useful improvements in igniting devices and 10 is particularly designed for the ignition of gas lights employed for the lighting of cigars, cigarettes, etc., although capable of general application.

The principal object of the invention is to 15 provide a device of this character which shall be extremely simple and durable in construction as well as efficient in operation and capable of being cheaply and easily manufactured as well as placed into use.

20 Another object of the invention is to provide an igniting device for gas burners, making use of operating mechanism including lazy tongs, with yieldable means to normally maintain the lazy tongs collapsed with the 25 igniter *per se* of the device lowered at one side of the burner, and means for manually extending the lazy tongs so as to elevate and laterally move the igniter *per se* and to immediately instantaneously actuate the latter 30 when the lazy tongs have been fully extended with the igniter *per se* directly above the outlet of the burner.

A further object of the invention is to 35 provide an improved igniter construction and co-operative mechanism upon lazy tongs whereby the device is normally in a lowered inoperative position and whereby, when the igniter is raised to an operative position, the igniter *per se* will be actuated, the co- 40 operative connections between the lazy tongs and the igniter *per se* including a trip device and means for automatically resetting the trip device when the igniter *per se* is lowered.

45 Other objects will become apparent as the nature of the invention is better understood, and the same consists of the novel form, combination and arrangement of parts hereinafter more fully described, shown in the 50 accompanying drawings and claimed.

In the drawings, wherein like reference characters indicate corresponding parts throughout the several views,

Figure 1 is a side elevational view of a 55 gas burner equipped with an igniting device constructed in accordance with the present

invention, with the igniter *per se* in its normal or lowered inoperative position,

Fig. 2 is a top plan view of the device shown in Fig. 1, 60

Fig. 3 is a rear elevational view thereof,

Fig. 4 is a detail view of the igniter *per se*, partly in top plan and partly in horizontal section,

Fig. 5 is a view similar to Fig. 1 with the 65 igniter *per se* in its raised position just prior to release of the trip,

Fig. 6 is a fragmentary view showing the upper portion of the device shown in Fig. 5, after release of the trip, 70

Fig. 7 is a perspective view of the pivoted igniter member,

Fig. 8 is a similar view of the flint carrying link,

Fig. 9 is a similar view of the trip operating catch for the pivoted member shown in Fig. 7, 75

Fig. 10 is a similar view of the trip carrying link which releases the catch of Fig. 9, and 80

Fig. 11 is a similar view of the milled or rough steel member which is carried by the pivoted member of Fig. 7 and which is yieldingly engaged by the flint carried by the member shown in Fig. 8. 85

Referring more in detail to the several views, the igniting device of the present invention is herein shown, for the sake of illustration, as operatively associated with a gas burner tip 5 provided on the outlet end of a gas supply pipe 6, the burner 5 being formed with an integral mixer 7 removably carried by a sleeve 8 which is threaded onto the pipe 6 in the usual manner. The present invention embodies an angular supporting strip 9, the horizontal end of which is apertured so as to be slid onto the upper end of the pipe 6, where it is secured in place between the shoulder 10 of said pipe 6 and the lower end of the sleeve 8 which is 100 threaded thereon.

The vertical end portion of the angular supporting member 9 is provided with a longitudinal elongated slot 11 which is engaged by a guide pin 12 carried by one of the links 105 of the lazy tongs 13 whereby rectilinear movement of the parts is insured, and whereby lateral swinging movement of the lazy tongs is prevented which would otherwise occur as will be apparent. The lazy tongs is connected with the vertical member of the support 9 by means of a pivot pin 14 which 110

passes through the two lowermost crossed links and which is rigidly supported by said support 9, the pivot pin 14 being in line with the slot 11 and immediately below the latter. The pin 14 is of such length as to receive the coils of the axial tensioned spring 15, and the extreme ends of this spring are bent to engage beneath the lower edges of said lowermost crossed links of the lazy tongs, whereby the spring 15 normally causes lapse of the lazy tongs. These mentioned two links are twisted at right angles at their lower end portions to provide handles 16 which, when pressed together, against the action of spring 15, causes extension of the lazy tongs.

As shown in Fig. 8, one of the uppermost links of the lazy tongs 13 is made considerably longer than the rest, this link being designated by the numeral 17, and the upper end portion of this link is bent upon itself to extend laterally as at 18 toward the burner tip 5. The link is then bent at right angles as at 19, 20 and 21 to provide a substantially rectangular portion forming a flint holder. Alined openings 22 are provided through the rectangular flint holder, and the flint element 23 is secured in a sleeve 24 which extends through one of the openings 22 and which is removably carried upon the inner end of an adjusting screw 25 which is threaded into the other opening 22.

Still another pair of openings 26 is provided through the flint holder, and a pivot pin 27 is rigidly secured in said openings, the pin 27 being of such length as to project through the flint holder for a short distance where it has a pivot member 28 mounted thereon, a spring 29 being interposed between the pivoted member 28 and a head 30 on the end of the pin 27, whereby the member 28 is yieldingly urged toward the flint holder. One end of the pivot member 28 is formed into U-shape as at 31, and a roughened wedge-shaped plate of steel 32 or the like is forced tightly into this U-shaped portion 31, whereby the roughened surface of the steel 32 is presented in contact with the end face of the flint element 23, the spring 29 keeping constant yielding contact at this point. Another axial spring 33 is provided upon the pin 27 between the apertured portions of the flint holder, and one end of this spring 33 is bent as at 34 to engage the end of the pivoted member 28 at one side of the pin 27, while the other end of said spring 33 is bent as at 35 to engage the adjacent end of the flint holder at the opposite side of pin 27. The spring 33 thus normally holds the member 28 substantially parallel with the apertured sides of the flint holder, the bent end 34 of the spring 33 being arranged to engage the lateral portion 18 for limiting the upward tilting movement of the member 28 at that side of the pin 27. The rough

plate 32 is notched as at 36 to embrace a portion of the rectangular end 31 of the member 28 to insure against longitudinal displacement of the plate 32 from said U-shaped end.

The other upper link of the lazy tongs is considerably shorter than the first and is indicated at 37, the same being pivoted at its central portion to the longer link 17 and being stamped and bent adjacent its inner end to provide a pivot stud 38 to which one end of a catch 39 is pivoted, the other end of said catch being notched as at 40 to be engaged by the lateral leg 41 of a tong 42 which is provided upon the end of the pivoted member 28 opposite that which is formed with the U-shaped portion 31. The end portion of the tong 42 is disposed in spaced relation to and parallel with another leg 43 on this end of the pivoted member 28, and the upper end of the catch 39 is bent at right angles as at 44 to engage the leg 43 and act as a stop for the member 28 when said catch 39 is released. A lug 45 extends laterally from the free end portion of the leg 43, and a comparatively weak axial spring 46 is secured upon this lug 45 with one end bearing upon the leg 43 and its other end engaging the adjacent edge of the catch 39, whereby the latter is normally forced in forwardly swung position to cause engagement between the lateral portion 41 and the upper wall of the notch 40. The link 37 is provided with an end lug 47 upon its outer or upper end arranged to engage the front edge of the catch 39 when the lazy tongs are extended as shown in Figs. 5 and 6 for forcing the catch 39 rearwardly so as to disengage it from the lateral portion 41. When this takes place the member 28 is swung upon its pivot instantaneously by the spring 33 so as to rapidly wipe the roughened face of the plate 32 across the end of the flint element 23, thus causing a spark directly above the burner tip 5. In actual practice, the downward movement of the plate 32 across the face of the flint element 23 causes the sparks to be projected directly onto the burner tip and insures ignition of the gas at the latter. As the flint element wears away, this wear is automatically taken up to a great extent by the spring 29, and additional adjustment can be obtained by screwing the member 25 inwardly. As soon as the spark has been obtained, the handles 16 are released, and the parts returned to their normal position as shown in Fig. 1.

What is claimed as new is:—

1. In combination with a burner and an igniter therefor, means to normally support said igniter in a lowered position at one side of said burner and manually operable to raise the igniter to a point above said burner, of means automatically operable upon raising of the igniter above the burner, for actuating said igniter so as to pro-

- duce sparks for igniting fuel issuing from said burner, said raising means including manually actuated lazy tongs normally spring pressed in collapsed condition, said 5 igniter including a pivoted member normally maintained swung in one direction, and yieldably movable in the opposite direction, said automatic means including a pivoted latch normally spring pressed into engagement with said pivoted member and swinging the same from its normal position upon extension of said lazy tongs, and an upper link of said lazy tongs having a lateral lug arranged to release said catch 10 upon complete extension of said lazy tongs.
2. In combination with a burner and an igniter therefor, means to normally support said igniter in a lowered position at one side of said burner and manually operable 20 to raise the igniter to a point above said burner, of means automatically operable upon raising of the igniter above the burner, for actuating said igniter so as to produce sparks for igniting fuel issuing from said 25 burner, said raising means including manually actuated lazy tongs normally spring pressed in collapsed condition, said igniter including a pivoted member normally maintained swung in one direction, and yieldably 30 movable in the opposite direction, said automatic means including a pivoted latch normally spring pressed into engagement with said pivoted member and swinging the same from its normal position upon extension of 35 said lazy tongs, an upper link of said lazy tongs having a lateral lug arranged to release said catch upon complete extension of said lazy tongs, and means to automatically reset the pivoted member and the catch 40 upon collapsing of said lazy tongs.
3. In combination with a burner and an igniter therefor, means to normally support said igniter in a lowered position at one side of said burner and manually operable to 45 raise the igniter to a point above said burner, of means automatically operable upon raising of the igniter above the burner, for actuating said igniter so as to produce sparks for igniting fuel issuing from said 50 burner, said raising means including manually actuated lazy tongs normally spring pressed in collapsed condition, said igniter including a pivoted member normally maintained swung in one direction, and yieldably 55 movable in the opposite direction, said automatic means including a pivoted latch normally spring pressed into engagement with said pivoted member and swinging the same from its normal position upon extension of 60 said lazy tongs, an upper link of said lazy tongs having a lateral lug arranged to release said catch upon complete extension of said lazy tongs, means to automatically reset the pivoted member and the 65 catch upon collapsing of said lazy tongs, an angular supporting member rigidly secured upon the burner and including a horizontal attaching portion with a vertical portion extending therefrom provided with a longitudinal elongated slot, said lazy tongs having its lower crossed links pivoted to said vertical portion beneath said slot, and a pin carried by one of the links of the lazy tongs above the pivot of the latter and slidably projecting through said slot. 75
4. An igniting device of the class described including a pair of lazy tongs, said lazy tongs including a relatively short upper link having a lateral lug on the upper end thereof and having a catch pivoted thereto, 80 said lazy tongs further including a second longer upper link having its free end portion bent to provide a flint holder, a flint element mounted in said flint holder, a pivoted member carried by the flint holder and 85 having a roughened member mounted therein bearing on said flint element, means to normally swing the pivoted member in one direction, means carried by said pivoted member and engageable with the catch 90 whereby said pivoted member is swung in the opposite direction upon extension of said lazy tongs, said lateral lug of the shorter upper link being arranged in the path of said catch to release the latter from 95 said last named means upon extension of the lazy tongs whereby said pivoted member is automatically swung to its normal position for causing movement of the roughened member across the flint element. 100
5. An igniting device of the class described including a pair of lazy tongs, said lazy tongs including a relatively short upper link having a lateral lug on the upper end thereof and having a catch pivoted thereto, said 105 lazy tongs further including a second longer upper link having its free end portion bent to provide a flint holder, a flint element mounted in said flint holder, a pivoted member carried by the flint holder and having a 110 roughened member mounted therein bearing on said flint element, means to normally swing the pivoted member in one direction, means carried by said pivoted member and engageable with the catch whereby said pivoted member is swung in the opposite direction upon extension of said lazy tongs, said lateral lug of the shorter upper link being arranged in the path of said catch to release the latter from 115 said last named means upon extension of the lazy tongs whereby said pivoted member is automatically swung to its normal position for causing movement of the roughened member across the flint element, and means carried by the pivoted member to normally maintain the catch 120 yieldingly in latching position. 125
6. An igniting device of the class described including a pair of lazy tongs, said lazy tongs including a relatively short upper link 130

having a lateral lug on the upper end thereof and having a catch pivoted thereto, said lazy tongs further including a second longer upper link having its free end portion bent 5 to provide a flint holder, a flint element mounted in said flint holder, a pivoted member carried by the flint holder and having a roughened member mounted therein bearing on said flint element, means to normally 10 swing the pivoted member in one direction, means carried by said pivoted member and engageable with the catch whereby said pivoted member is swung in the opposite direction upon extension of said lazy tongs, said 15 lateral lug of the shorter upper link being arranged in the path of said catch to release the latter from said last named means upon extension of the lazy tongs whereby said pivoted member is automatically swung to 20 its normal position for causing movement of the roughened member across the flint element, means carried by the pivoted member to normally maintain the catch yieldingly in latching position, a support, means for 25 guiding the lazy tongs relative to said support when being contracted and expanded, and means for securing the lazy tongs to said support.

7. An igniting device of the class described 30 including a pair of lazy tongs, said lazy tongs including a relatively short upper link having a lateral lug on the upper end thereof and having a catch pivoted thereto, said lazy tongs further including a second longer 35 upper link having its free end portions bent to provide a flint holder, a flint element mounted in said flint holder, a pivoted member carried by the flint holder and having a roughened member mounted therein bearing 40 on said flint element, means to normally swing the pivoted member in one direction, means carried by said pivoted member and engageable with the catch whereby said pivoted member is swung in the opposite direction 45 upon extension of said lazy tongs, said lateral lug of the shorter upper link being arranged in the path of said catch to release the latter from said last named means upon extension of the lazy tongs whereby said

pivoted member is automatically swung to 50 its normal position for causing movement of the roughened member across the flint element, means carried by the pivoted member to normally maintain the catch yieldingly in latching position, a support, means for 55 guiding the lazy tongs relative to said support when being contracted and expanded, and means for securing the lazy tongs to said support, said last named means including a pivot pin for the lower crossed links of the 60 lazy tongs.

8. An igniting device of the class described including a pair of lazy tongs, said lazy tongs including a relatively short upper link having a lateral lug on the upper end thereof 65 and having a catch pivoted thereto, said lazy tongs further including a second longer upper link having its free end portion bent to provide a flint holder, a flint element mounted in said flint holder, a pivoted member carried by the flint holder and having a roughened member mounted therein bearing 70 on said flint element, means to normally swing the pivoted member in one direction, means carried by said pivoted member and 75 engageable with the catch whereby said pivoted member is swung in the opposite direction upon extension of said lazy tongs, said lateral lug of the shorter upper link being arranged in the path of said catch to release 80 the latter from said last named means upon extension of the lazy tongs whereby said pivoted member is automatically swung to its normal position for causing movement of the roughened member across the flint element, means carried by the pivoted member to normally maintain the catch yieldingly 85 in latching position, a support, means for guiding the lazy tongs relative to said support when being contracted and expanded, means for securing the lazy tongs to said support, said last named means including a pivot pin for the lower crossed links of the 90 lazy tongs, and a spring for normally holding said lazy tongs in collapsed condition having its coils encircling said pivot pin.

In testimony whereof I affix my signature.
EDWARD JURKOWSKI.
